The ornamental design for a lid for cups, as shown and described.

DESCRIPTION

FIG. 1 is a side and top perspective view of a lid for cups, showing my new design;

FIG. 2 is a side elevational view thereof, the other side elevational views of the device rotated 90° about a horizontal axis lying in the plane of the drawing being identical thereto;

FIG. 3 is an elevational view thereof from the bottom of FIG. 2;

FIG. 4 is an elevational view thereof from the top of FIG. 2;

FIG. 5 is a side and top perspective view of a second embodiment of a lid for cups, showing my new design;

FIG. 6 is a side elevational view thereof, the other side elevational views of the device rotated 90° about a horizontal axis lying in the plane of the drawing being identical thereto;

FIG. 7 is an elevational view thereof from the bottom of FIG. 6;

FIG. 8 is an elevational view thereof from the top of FIG. 6;

FIG. 9 is a side and top perspective view of a third embodiment of a lid for cups, showing my new design;

FIG. 10 is a side elevational view thereof, the other side elevational views of the device rotated 90° about a horizontal axis lying in the plane of the drawing being identical thereto;

FIG. 11 is an elevational view thereof from the bottom of FIG. 10;

FIG. 12 is an elevational view thereof from the top of FIG. 10;

FIG. 13 is a side and top perspective view of a fourth embodiment of a lid for cups, showing my new design;

FIG. 14 is a side elevational view thereof, the other side elevational views of the device rotated 90° about a horizontal axis lying in the plane of the drawing being identical thereto;

FIG. 15 is an elevational view thereof from the bottom of FIG. 14;

FIG. 16 is an elevational view thereof from the top of FIG. 14;

FIG. 17 is a side and top perspective view of a fifth embodiment of a lid for cups, showing my new design;

FIG. 18 is a side elevational view thereof, the other side elevational views of the device rotated 90° about a horizontal axis lying in the plane of the drawing being identical thereto;

FIG. 19 is an elevational view thereof from the bottom of FIG. 18;

FIG. 20 is an elevational view thereof from the top of FIG. 18;

FIG. 21 is a side and top perspective view of a sixth embodiment of a lid for cups, showing my new design; and,

FIG. 22 is a side elevational view thereof, the other side elevational views of the device rotated 90° about a horizontal axis lying in the plane of the drawing being identical thereto.
